[57] CLAIM

The ornamental design for a diaper for incontinent persons, as shown.

DESCRIPTION

FIG. 1 is a front elevational view of a diaper for incontinent persons, showing my new design;
FIG. 2 is a side elevational view thereof, the left side elevational view being identical;
FIG. 3 is a bottom plan view thereof; and
FIG. 4 is a reduced top plan view thereof in open condition.

FIG.3

FIG.1

FIG.2

FIG.4
